UNITED STATES PATENT OFFICE.

AUGUST E. JOHNSON, OF OSAGE CITY, KANSAS.

OIL-CAN.

SPECIFICATION forming part of Letters Patent No. 516,540, dated March 13, 1894.

Application filed October 5, 1893. Serial No. 487,255. (No model.)

To all whom it may concern:

Be it known that I, AUGUST E. JOHNSON, of Osage City, in the county of Osage and State of Kansas, have invented certain new and useful Improvements in Oil-Cans, of which the following is a full, clear, and exact description, reference being had to the accompanying drawings, which form a part of this specification.

10 My invention relates to certain new and useful improvements in oil cans, which may also be used as a gasoline can or other liquid containing vessel; and my invention consists in certain features of novelty hereinafter described and pointed out in the "claims."

Figure I, is a perspective of my improved can. Fig. II, is a vertical section taken on line II, II, Fig. I.

Referring to the drawings: 1, represents the body of the can having the usual opening 2, for filling the can and cap-piece 3, the can, having a stem 4, with a central aperture 5, leading into the can for the purpose of supporting an air bulb 6, by the compression of which air is forced into the can and the oil is caused to be discharged through a tube 7, leading down nearly to the bottom of the can, and being preferably provided with apertures 8, for admitting the liquid or air to the tube. As the air passes down on the surface of the liquid, the same passes up through the tube 7, and out through a connecting hose 9, having a tip 10, thereon, by which the liquid or oil may be conveyed in to a lamp 11. The connecting medium 9, may be either a flexible hose or other tube; but I have found in practice that a hose is more convenient as the same can be readily removed from the upper end of the tube 7, for the purpose of packing, cleaning, &c. The tube being flexible it may also be wound around the bulb on the top of the can, thus being entirely out of the way.

To the side of the can I attach one or more plates 12, said plates standing out from the side of the can and leaving an aperture 13, between the plate and the can. I have shown but two plates; but more may be placed on the side of the can if desired. In the plates 12, I form a recess 14, for the purpose of allowing a hand-piece 15, on the end of the stem 16 of the wick raiser to be inserted behind the plates, the stem of the wick raiser pass-

ing down through said recess 14, to the bottom of the same. The recess 14, not being 55 as wide as the hand-piece of the wick raiser, confines said hand-piece between said plate and can, therefore holding the burner 17 in a supported position to the side of the can, allowing the lower end of the wick 18, to remain within the opening 19, of the lamp while the lamp is being filled, thus providing 60 a ready and convenient means for supporting the burner with the lower end of the wick remaining in the lamp in order to prevent drip 65 outside of the lamp while the lamp is being filled.

I have shown two of the plates 12, in order that the can would be suitable for supporting a burner of a lamp of greater or less height. 70

I claim as my invention—

1. As a new article of manufacture, a can for containing liquids having plates on its side with apertures into which the stem of the wick raiser of a burner may be placed in 75 order to support said burner during the filling of the lamp;—substantially as described and for the purpose set forth.

2. In a can for containing liquids, the combination of a suitable can; plates on the side 80 of the can having a recess between the plates and can, whereby the hand-piece of a wick raiser may be inserted in said recess, and a slot in said plates permitting the stem of the wick raiser to pass downward in order to secure the hand-piece at the rear of the same; substantially as and for the purpose set forth. 85

3. In a can for containing liquids, the combination of a suitable can, a tube in said can having perforations for the discharge of said 90 liquid; a bulb on said can for compressing the air; a connecting medium between said tube plates on the side of the can having a recess between the plates and can, whereby the hand piece of wick-raiser may be inserted in said 95 recess and a slot in said plates permitting the stem of the wick-raiser to pass downward in order to secure the hand piece at the rear of the same for supporting the lamp burner during the process of filling the lamp; sub- 100 substantially as and for the purpose set forth.

AUGUST E. JOHNSON.
